UNITED STATES PATENT OFFICE

130,512

DESIGN FOR A SHOE LACE

Arthur D. Anderson, Jr., Milton, Mass., assignor to United Shoe Machinery Corporation, Flemington, N. J., a corporation of New Jersey

Application December 20, 1940, Serial No. 97,478

Term of patent 14 years

To all whom it may concern:

Be it known that I, Arthur D. Anderson, Jr., a citizen of the United States, residing at Milton, in the county of Norfolk and Commonwealth of Massachusetts, have invented a new, original, and ornamental Design for Shoe Laces, of which the following is a specification, reference being had to the accompanying drawing, forming a part thereof.

The figure is a perspective view of a shoe lace showing my new design, the part shown in broken lines to be completed in the same manner as the part shown in full lines.

The dominant feature of my design resides in the completely napped appearance of the same.

I claim:

The ornamental design for a shoe lace, substantially as shown and described.

ARTHUR D. ANDERSON, JR.
